Ms. 624

Conrad Harris & Paul Wm. Joiner of Cincinnati, Ohio.

Assignors to

Alexander Bradley of Pittsburgh, Pa.

Letters Patent No. 624. Dated Jan. 31st, 1854.

The schedule referred to in these Letters Patent, and making part of the same.

To all whom it may concern:

Be it known that we, Conrad Harris and Paul Wm. Joiner, of Cincinnati, Hamilton County, State of Ohio, have invented or produced a new and useful design for cooking stoves, and they do hereby declare the following to be a full and exact description of the same, reference being had to the accompanying drawings, and to the letters of reference marked thereon, to wit, letter B being a perspective view of the stove.

What we claim as our invention and desire to secure by Letters Patent, is the ornamental design for a stove, as represented in the annexed drawings.

Witnesses:

Peter Bell,
J. S. Hyatt.

Conrad Harris,
Paul W. Joiner.
